(57) **CLAIM**

The ornamental design for a flexible camera mount, as shown and described.

DESCRIPTION

FIG. 1 is a top, front, right isometric view of the flexible camera mount in a basic configuration;

FIG. 2 is a top plan view thereof;

FIG. 3 is a bottom plan view thereof;

FIG. 4 is a right side elevation view thereof, the left side elevation view being a mirror image of the right side elevation view;

FIG. 5 is a front elevation view thereof, the rear elevation view being a mirror image of the front elevation view;

FIG. 6 is a top, front right isometric view of the flexible camera mount in first posed configuration;

FIG. 7 is a rear elevation view thereof, the front elevation view being a mirror image of the rear elevation view;

FIG. 8 is a right side elevation view thereof;

FIG. 9 is a top, front, right isometric view of the flexible camera mount in a second posed configuration;

FIG. 10 is a front elevation view thereof;

FIG. 11 is a rear elevation view thereof;

FIG. 12 is a left side elevation view thereof, the right side elevation view being a mirror image of the left side elevation view;

FIG. 13 is a top plan view thereof, the bottom plan view being a mirror image of the top plan view;

FIG. 14 is a top, front, right isometric view of the flexible camera mount in a third posed configuration;

FIG. 15 is a front elevation view thereof;

FIG. 16 is a rear elevation view thereof;

FIG. 17 is a top plan view thereof;

FIG. 18 is a bottom plan view thereof;

FIG. 19 is a left side elevation view thereof, the right side elevation view being a mirror image of the left side elevation view;

FIG. 20 is a top, front, right isometric view of the flexible camera mount in a fourth posed configuration;

FIG. 21 is a front elevation view thereof, the rear elevation view being a mirror image of the front elevation view;

(Continued)

FIG. 22 is a right side elevation view thereof, the left side elevation view being a mirror image of the right side elevation view; and,

FIG. 23 is a top plan view thereof.

The broken, lines in FIGS. 1-23 that are located immediately adjacent the shaded areas represent the bounds of the claimed design, while all other broken lines are directed to the environment. All of the broken lines form no part of the claimed design.

1 Claim, 23 Drawing Sheets
